UNITED STATES PATENT OFFICE.

JOSHUA M. PHILBROOK, OF SCAPPOOSE, OREGON.

POWER-GENERATING SYSTEM.

1,416,867.

Specification of Letters Patent. Patented May 23, 1922.

Application filed December 12, 1918. Serial No. 266,467.

To all whom it may concern:

Be it known that I, JOSHUA M. PHILBROOK, a citizen of the United States of America, residing in Scappoose, in the county of Columbia, in the State of Oregon, have invented a certain new and useful Power-Generating System, of which the following is a specification, reference being had to the accompanying drawings.

10 My invention relates to the promotion of the generation of power, and has for a principal object direct means for converting motive power derived from impulses intermittently or at intervals into a constant or un-intermittent motive power.

Another object is to augment the constant power derived from an intermitting source by accretion obtained from said source independent of the source considered only as a 20 motive power.

More specifically, the object of my invention is to provide means for utilizing the force of recurrent explosions to build up a source of fluid pressure supply from which 25 an ultimate constant motive power may be drawn at will.

The fluid pressure supply which I employ as an ultimate force may be either air or water, each of which has its advantages.

30 Air is especially suitable for smaller plants, although it may be used for large ones, and in its use provision is made for utilizing directly the heat generated in producing the explosions in addition to the motive power of the explosion as a means for augmenting the ultimate constant power.

Water, on the other hand, may perhaps be used to greater economy.

In apparatus embodying my invention incidental advantages in addition to the broader features above enumerated will appear to one skilled in the art.

What constitutes my invention will be hereinafter specified in detail and succinctly 45 set forth in the appended claims.

In the accompanying drawings—

Figure I presents by way of example a medial vertical sectional view partially in elevation of apparatus embodying my invention and affords diagrammatic illustration of my invention adapted for the utilization of air as an ultimate motive fluid of constant force.

Fig. II correspondingly illustrates appa-

ratus embodying my invention adapted for 55 the utilization of water as the ultimate motive fluid.

Fig. III is a detail vertical section of a float-controlled electric circuit-maker applicable to both forms of apparatus shown in 60 the preceding figures.

The following description applies first to Figure I.

Referring to the numerals on the drawings, 1 indicates an airtight reservoir which 65 may be constructed of any suitable material and according to any preferred method and design. For diagrammatical purposes it is sufficiently illustrated as made in one piece and integrally with a diaphragm 2 that extends partially across its upper internal diameter, and likewise with a chamber 3 that depends from the diaphragm and extends downwardly to a point above the bottom 4 of the reservoir 1. Both the reservoir and 70 the chamber 3 may be of any suitable and preferred shape, but that of the latter is preferably cylindrical.

The space between the reservoir and chamber is closed by a transverse partition 80 5 preferably located near the top of the chamber 3. It is provided with one or more inwardly opening spring-supported valves 7 and one or more spring-depressed outwardly opening valves 8.

Within the chamber 3 I provide a sufficiently close fitting buoyant member or piston-float 9. It is preferably a hollow structure whose top 10 is preferably overlaid with a covering of fire brick or other 90 heat-resisting material, so as to constitute a floor to the combustion chamber 11 that is defined by the top 10 and the side walls of the chamber 3 and diaphragm 2. Into the interior of the combustion chamber lead 95 one or more pairs of pipes, whereof 12 indicates an air-supply pipe and 14 a fluid-fuel supply pipe. Those pipes are relatively proportioned and regulated, as to supply, so as to discharge into the combustion chamber 100 air and fluid fuel (gas, pulverulent fuel, or oil,) in proportions and under pressure suitable to effect an explosive compound. Means for regulating the communication and ignition of an explosive charge at predetermined 105 intervals of recurrence, being well understood in the art relating to internal combustion engines, for example, are deemed to require

in themselves neither illustration nor description.

For utilizing the waste products of combustion as well as for scavenging the combustion chamber, I provide an eduction pipe 15 that communicates with the interior of the combustion chamber through a valve port 16 within which is seated a spring-closed valve 17 whose stem 18 is coaxial with the core of a solenoid 19 to which it is secured or of which it is made a part. The solenoid is placed in circuit with a source of electrical energy (not illustrated) by leads 20 and 21, by the aid of contact-making terminals 22 and 23. The former is stationary, being fixed as upon a support 25, that may be disposed at any convenient point upon the top of the reservoir 1, while the latter is movable into and out of contact with the former. Movement of the terminal 23 of the circuit-maker just described is automatically effected and timed by a float 26 that works loosely at any convenient point of disposition within the space between the side walls of the reservoir 1 and chamber 3. The float 26 is provided with a stem 27 that fits snugly within bearings 28 and 29 provided for it in the partition 5 and top of the reservoir 1, respectively, the float being of sufficient weight and buoyancy to insure its rise and fall with change of the water level 30 within the reservoir 1. The rising of the float 26 to a point predetermined to correspond with that at which the water lever 30 reaches substantially its maximum stage is timed with reference to discharge from the pipes 12 and 14, so that contact between the terminals is substantially synchronous with an interval between deliveries therefrom of successive explosive charges into the combustion chamber 11. The effect of the contact between the terminals 22 and 23, as will hereinafter more fully appear, is to open the valve port 16 by actuation of the valve 17, substantially at the moment when an explosive charge has done its work, and to close it preparatory to the admission into the chamber 11 of a fresh explosive charge. The eduction pipe 15 is in constant operative communication with a low pressure turbine 35, whereby the residual pressure of the spent charges or waste products of combustion from the chamber 11 may be utilized as often as the valve 17 is actuated to open the port 16. By aid of a pipe 31 communicating between the tail of the turbine 40 and the interior of the pipe 15, driving power in addition to that of the spent products of combustion within said pipe may be contributed, and the two turbines 35 and 40 compounded.

The reservoir 1 is a container for both air and water, the body of the latter being indicated by the reference numeral 36 in Fig.

I of the drawings. Its volume is fixed and preferably so proportioned to the capacity of the reservoir and the displacement efficiency of the piston-float 9, as to be kept confined within the reservoir 1 well below the partition 5. The upper part of the reservoir is reserved for air, that portion 37 above the partition 5 constituting an air tank or compartment for the storage of compressed air.

In this connection it may be emphasized that the drawing is diagrammatic only, no attempt being made therein more than to suggest adequate air storage capacity of the tank or means of provision therefor. Such details are, of course, merely mechanical and matters of degree, to be varied at discretion. Illustration, however, is made of an extension of said air storage compartment as indicated by the numeral 38 to correspond, substantially with the length of the eduction pipe 15; but such illustration is also diagrammatic and is intended only to indicate provision of means for keeping the waste products of combustion that are contained within the pipe 15 inside of the volume of air stored within the reservoir 1 until they may give up substantially all their heat in excess of atmospheric temperature, thereby contributing additional expansion to the air within the storage compartment.

40 indicates an air turbine engine which is illustrated by way of example of the principal means of utilizing the power derived from storage of compressed air within the compartment 37. The secondary turbine 35 cooperates and is compounded with the main turbine 40 in the manner already specified.

Description of the operation of the form of embodiment of my invention as specified above appearing to be here in order, it may be explained that the reservoir 1 being supplied with a sufficient volume of water 36, the apparatus is ready for service. The weight of the water lifts the piston-float 9 towards the diaphragm 2 to its limit of upward movement, which may be made to depend upon equilibrium of the forces employed. If now an explosive charge of air and fluid fuel is admitted through the pipes 12 and 14 into the combustion chamber 11 and there ignited, the effect will be to drive the piston-float 9 down against the volume of water 36 and to raise its level 30 against the volume of air confined above it within the reservoir 1 and its ramifications or extensions, the valve (or valves) 7 closing to prevent escape of air and the valve (or valves) 8 opening to receive and to entrap within the storage compartment such air as the pressure exerted may drive beyond them. Substantially at the same time that the member 9 reaches its limit of downward move-

ment, or in other words, when the force of the explosion is spent, the rise of the level 30 causes the float 26 to lift the terminal 23 into contact with the terminal 22, and thereby, in the manner previously specified, to actuate the valve and open the port 16. Relief of air pressure above the piston-float 9 enables its buoyancy aided by air pressure confined below the partition 5 to respond promptly to a drop of the level 30 in accordance with the well known hydrostatic law. At the drop of the level 30 the valve (or valves) 7 opens to admit influx of air. Thereupon the cycle of operation described continues to repeat itself until an equilibrium of forces is established, which is in practice, a state not to be reached so long as air is drawn from the compartment.

My invention contemplates the generation of high pressure air storage and by the employment of apparatus of requisite dimensions storage capacity to a practically unlimited extent may be attained.

In the form of embodiment of my invention shown in Fig. I provision is made for an intake of air at intervals, and for the employment of a fixed volume of liquid as an hydraulic medium of compression, air being the power-generating medium.

30 In Fig. II the means illustrated operates upon the same principle, but, dispensing with the use of air, employs water only as the power-generating medium.

Referring to the numerals on Fig. II, 50 indicates a tank having adequate means (not illustrated) of water supply and discharge adapted to maintain therein a substantially constant level 51. Supported within the tank 50 is a chamber 53 that corresponds in function and substantially in form to the chamber 3 above described. The chamber 53 communicates through a passage 54 and port 55 with a stand-pipe 56. The stand-pipe is representative of any form of water reservoir 45 within which a head of water may be maintained, the stand-pipe form being selected only for convenience in making diagrammatic illustration of my invention.

A port or plurality of ports 57 affords 50 means of communication for water between the interior of the tank 50 and that of the chamber 53. An inwardly opening caged valve 59 controls admission of water from the passage through each port 57, and one 55 or more outwardly opening caged valves 60 controls admission of water from the passage 54 to the stand-pipe 56.

60 61 indicates a piston-float corresponding in form, function, and operation to the piston-float 9 already described. Its top 62 forms the bottom of a combustion chamber 63 which is covered by a transverse partition 65 that completes the chamber 53. An air supply pipe 66 and a fluid-fuel supply pipe 65 67 communicate, respectively, with the in-

terior of the combustion chamber 63 in the manner and for a purpose corresponding to that of the pipes 12 and 14.

Means for scavenging the combustion chamber are necessary and may consist of a 70 by-pass 69 into and across which the partition 65 extends. An inwardly opening valve 70 seated in a port in the said partition within the interior of the by-pass 69 controls discharge of spent products of combustion from 75 the chamber 63, and may be operated by a solenoid 71 corresponding in every respect to the solenoid 19.

As has been specified the float 26 is applicable to either form of embodiment of my 80 invention herein shown, as a means of actuating contact-making terminals 22 and 23 for making and breaking circuit through the solenoid 71 in like manner as through the solenoid 19. 85

In Fig. II the float 26 is shown within a siphon 72 that contains a confined and fixed volume of water whose rise and fall within the siphon for actuating said float is effected by a plunger 73 on the bottom of the piston-float 61.

The chamber 53 is shown in Fig. II as provided with an extension 74 that constitutes the shell of a boiler having tubes 75 and a stack 76. Those elements are shown 95 by way of example of available means for utilizing the heat of the waste products of combustion from the chamber 63 but are non-essential. 77 indicates a water turbine that is in operative communication with the 100 stand-pipe 56 as through a service pipe 78. It is representative of means for utilizing the power of the head of water within the stand-pipe.

By way of description of the operation of 105 apparatus shown in Fig. II, it is necessary only to supplement the description of the operation of apparatus shown in Fig. I. Each pulsation of the piston-float 61 drives the water in the bottom of the chamber 53 11 and the passage 54 with violent impact against the valve or valves 60, thereby lifting the same and causing with each impact a quantity of water to enter the stand-pipe 56, wherein the closing of the valve 60 entraps it. Simultaneously, of course, the plunger 73 actuates the float 26 through the uplift of the level of water within the siphon 72. As soon as the explosive force which drives the piston-float 61 is spent the 12 weight of the water lifts it for repetition of its operation, the valve 59 opening to admit influx of a quantity of water through the port or ports 57 proportioned to that driven by impact as described through the port or 12 ports 55.

What I claim is:

1. In a power generating system, the combination of a cylinder having therein a combustion chamber spaced from the walls of 1:

said cylinder and open at its lower end, a body of liquid in the cylinder partially filling the combustion chamber and constituting a seal for the lower end of the chamber, 5 there being a space in said cylinder above the body of liquid, a piston float in said chamber actuated through its upward stroke by the rise in level of said fluid, means for admitting air into said cylinder above the 10 body of liquid, a valve controlled exhaust for the air from said cylinder, a receptacle for the compressed air issuing from said cylinder, and means for supplying at intervals and igniting explosive charges within said 15 chamber against the face of said piston.

2. In a power generating system, the combination with an engine comprising a combustion chamber open at one end, a piston-float operatively disposed within its open 20 end, and operative means for supplying and igniting explosive charges within said chamber, of a receptacle in operative communica-

tion with the piston-float and containing a power-storage fluid, of a liquid medium operatively disposed between the piston and 25 the power-storage fluid that serves to support the piston within the combustion chamber and to transmit accretions of power imparted to it by impact of the piston to the power-storage fluid within the receptacle, 30 and of two fluid motors in direct operative communication, one with the receptacle and the other with the interior of the combustion chamber, the former motor discharging into the source of supply of the latter where- 35 by the two motors are compounded.

In testimony whereof, I have hereunto set my hand in the presence of two subscribing witnesses.

JOSHUA M. PHILBROOK.

Witnesses:
